UNITED STATES PATENT OFFICE.

JULIAN G. GOODHUE, OF CHICAGO, ILLINOIS.

DISINFECTANT APPARATUS.

1,293,405.

Specification of Letters Patent.

Patented Feb. 4, 1919.

Application filed February 23, 1910, Serial No. 545,390. Renewed June 29, 1918. Serial No. 242,667.

To all whom it may concern:

Be it known that I, JULIAN G. GOODHUE, citizen of the United States, residing at Chicago, in the county of Cook and State of Illinois, have invented a certain new and useful Improvement in Disinfectant Apparatus, of which the following is a full, clear, concise, and exact description, reference being had to the accompanying drawings, forming a part of this specification.

My invention relates to disinfectant apparatus, and is of particular utility for toilet rooms, for bowls and the like, and in this application it is illustrated for this particular use, although various uses may be found for this invention.

Generally speaking, the apparatus comprises a spraying device, in connection with means for storing disinfectant liquid, the means being such as maintain the device in operative condition under varying conditions, additional means being provided to furnish an air jet periodically to the sprayer to eject the disinfectant liquid. Further advantageous features of my device contemplate the improvement of devices of this class in general, and also contemplate the provision of improved filling devices to restore the apparatus to its initial operative condition, after the supply of liquid has fallen low or become exhausted.

I will describe my invention more in detail by reference to the accompanying drawings illustrating one embodiment thereof, in which—

Figure 1 sets forth my improved device in connection with one of its uses;

Fig. 2 is a sectional view of my improved sprayer;

Fig. 3 is a detail view of the mounting brackets employed;

Fig. 4 is a detail view of the reservoirs used;

Fig. 5 is a top view of the reservoir shown in Fig. 4.

Referring more particularly to Fig. 1, my improved device is here shown as applied to a toilet room, in which a door check 1 is mounted upon a door 2, and an air pipe 3 leads from said door check to periodically convey an air jet through said pipe to a sprayer 4, mounted within a bowl 5, which sprayer is associated with my improved controlling mechanism 6, comprising reser-

voirs, as will be hereinafter more clearly explained.

Whenever the door is opened or closed, an air jet passes through the sprayer, and drawing disinfectant liquid therefrom sprays the surrounding parts. The details of the sprayer which I prefer to employ are more clearly set forth in Fig. 2, in which I have illustrated a T-shaped tube 7, closed at its lower portion by a cap 8, which cap forms a supply chamber for liquid, whose level is indicated in the illustration. A tube 9, hermetically sealed by virtue of the imperial coupling comprising the wedge-shaped member 10 and cap 11, is utilized to permit the entrance into the sprayer of the air tube 3, which forms at its left-hand extremity an air jet whenever the door check is operated by the door 2. A second tube 12, leading to the controlling mechanism 6, also enters through the tube 9, and has its lower end immersed in the liquid in the cup 8. A further tube 13 has its lower extremity immersed in the same liquid, and has a small opening 14 at its opposite extremity, directly underneath the air jet. These two tubes 3 and 13 leave the interior of the spraying device through the end portion 15. A hood 16, which, in this instance I prefer to call a "nozzle", covers the extremities of the tubes 3 and 13, and prevents injury thereto. The interior of the T-shaped tube 7 is under atmospheric pressure.

The controlling apparatus 6 consists preferably of a main reservoir, comprising an upturned receptacle 17, having its open mouth at the lower extremity thereof, at the neck 18, which main reservoir 17 projects into what I prefer to call an "auxiliary reservoir" 19. These main and auxiliary reservoirs are mounted, through the agency of the improved bracket arrangement, shown more clearly in Fig. 3, although this illustration is on a much larger scale than the apparatus shown in Fig. 4.

This bracket construction comprises an upper bracket member 20, whose upper end engages a recess 21, provided in the top of the main reservoir, and a second bracket member 22, designed to enter the recess 23, on the bottom face of the auxiliary reservoir 19. Between the two bracket members 20 and 22, I provide a channel member 24, which has offsets, corresponding to

ears, provided upon the members 20 and 22, so that these members may coöperate in holding the device in place.

In the preferred method of mounting the apparatus, the bracket 20 is first secured to the wall by means of screws 25, whereupon the channel member 24 is mounted in place, then the main and auxiliary reservoirs, 17, 19, and thereafter, the bracket member 22 is mounted in place and screwed to the wall by means of screws 26.

The main reservoir is closed, except at its mouth, which projects within the reservoir 19. This auxiliary reservoir, however, has communication with atmospheric air. Liquid is provided in the main reservoir 17, such liquid being shown at a given height in the illustration, and this liquid slowly finds its way into the auxiliary reservoir 19, remaining at the level indicated, namely, the bottom of the neck 18, and no air can enter the main reservoir 17, except as the level of the liquid in the auxiliary reservoir 19 falls below the lowermost portion of the neck 18. The tube 12, it will be seen, enters through a recessed portion 27, provided in the receptacle, forming the main reservoir 17, and extends down into the liquid within the auxiliary reservoir. This tube 12, it will be remembered, also extends into the liquid within the cup 8, and the tube 12 is arranged in the form of a siphon, in order to maintain the level of the liquid in the cup 8, at the same level as the liquid in the auxiliary reservoir 19.

The operation of the device thus far will be apparent. Liquid is maintained at a given level in the sprayer, through the operation of the main and auxiliary reservoirs 17 and 19, and the supply chamber within the cup 8, and whenever a jet of air is blown through the tube 3, liquid is sprayed from the sprayer, and this liquid again replenished from the auxiliary reservoir 19, whereupon air enters through the neck 18, into the main reservoir 17, allowing the liquid therefrom to drop, and maintaining the level of the liquid in the auxiliary reservoir 19. It will be seen from this illustration that I provide a large air space above the liquid in the auxiliary reservoir, which large air space allows for the contraction and expansion of the air and liquid in the inclosed portions of the device, thus to prevent over-flowing or improper action of the device.

In order to fill the main reservoir, I provide a tube 28, which extends to very nearly the top of the main reservoir 17. This tube is designed for connection to a pump as will be more clearly explained hereinafter.

In order to supply liquid at the same time the air is being exhausted, I provide a tube 29, which extends down into the reservoir to a place a short distance above the level of the liquid, and which tube 29 is also

adapted for connection with a pump, as may be explained hereinafter. A hole 30 is provided in the tube 28, which hole permits liquid from the auxiliary reservoir 19 to enter said tube, thereby to prevent air from entering the main reservoir 17 through said tube 28, after the device has been filled, the entrance of which air would permit the liquid from the main reservoir to flow from said main reservoir to the auxiliary reservoir and thence overflow. This aperture 30 therefore accomplishes a very useful and highly beneficial purpose in thus sealing the device.

The apparatus herein shown is filled by withdrawing the air from the vessel 17 and supplying liquid to the same. This may be done by any suitable apparatus, a convenient form of which is shown in my Patent No. 1,070,681, issued August 19, 1913.

While I have herein shown and particularly described the preferred embodiment of my invention, I do not desire to limit myself to the precise construction and arrangement herein set forth, but having thus described my invention, what I claim as new and desire to secure by Letters Patent is:

1. A device of the class specified, comprising a door check adapted and arranged to act as an air pumping device, a lavatory bowl, a distributing device located within said bowl, said distributing device having a small reservoir, an air pipe extending from said door check to said distributing device, the latter being provided with a reservoir pipe coöperating with the air pipe to withdraw liquid from said reservoir and distribute the same within the bowl, and a relatively large reservoir apparatus arranged outside of the bowl and having a feed connection with the distributing device reservoir for supplying the latter with said liquid material.

2. A device of the class specified, comprising an air pumping device, a lavatory bowl, a pneumatically operated distributing device having a small reservoir located in the lavatory bowl, a pneumatic connection between said pumping device and said distributing device for operating the latter, a supplemental reservoir outside the lavatory bowl and a siphon connection between said supplemental reservoir and said small reservoir for filling the latter.

3. A device of the class specified, comprising an air pumping device, a lavatory bowl, a pneumatically operated distributing device located within the lavatory bowl and having a small liquid reservoir, a pneumatic connection between said pumping device and said distributing device for operating the latter, and a relatively large reservoir device located outside of the lavatory bowl and having a feed connection for feeding liquid into the reservoir of said distributing device.

4. In apparatus of the class specified, the combination of a lavatory bowl, a pneumatically operated distributing device located in the bowl and a pneumatic connection extending to the bowl and arranged to coöperate with said distributing device for operating the same, said connection being extended over the top of the bowl and serving as a support for said device. 45
- 5 5. In apparatus of the class specified, the combination of a door check adapted and arranged to act as an air forcing device, a lavatory bowl, a distributing device located at said bowl and having a liquid reservoir, an air pipe extended from said door check to and into said distributing device and provided with an air port located within said distributing device, a reservoir pipe with said distributing device extended from the reservoir thereof to the air port of said distributing device so as to coöperate with the air port of said door check air pipe to withdraw liquid from said reservoir and distribute the same in the lavatory bowl, a relatively large reservoir apparatus located outside of but near said bowl and a feed pipe extending from said large reservoir apparatus to and into said distributing device to supply liquid to the reservoir thereof. 60
- 10 6. In apparatus of the class specified, the combination with means operable by the movement of a door for producing an air current, a lavatory bowl, a distributing device operable by the air current and located within said bowl, said distributing device having a small reservoir, a pneumatic connection between said air current producing means and said distributing device for operating the latter, a second or supplemental reservoir outside of the bowl and a tube or pipe connection between said supplemental reservoir and said distributing device for supplying liquid to the latter. 65
- 15 7. The combination of a door check ar-
- ranged to act as an air forcing device, a tubular connection running from said door check, an atomizer having a small reservoir and arranged to be operated by an air blast, said tubular connection from said door check running to said atomizer and being arranged to operate the same, a large reservoir located near said atomizer, and a siphon feed connection between said large reservoir and atomizer for supplying the latter with liquid from the former. 70
- 20 8. The combination of a door check having a side port, a tube or pipe connected with the side port of said door check, an atomizer connected with said tube or pipe and having a small reservoir and also having means whereby liquid from said reservoir is sprayed or atomized by an air blast from said door check, a large reservoir located near said atomizer, said large reservoir having means whereby a substantially uniform liquid level is maintained with it, and a siphon connection between said large reservoir and said atomizer for supplying the reservoir of the latter with liquid from said large reservoir. 75
- 25 9. The combination of a door controlling the entrance to a lavatory, a door check co-operating with said door, a bowl within said lavatory, a pneumatic tube or pipe extending from said door check to said bowl, an atomizer within the bowl connected to said tube or pipe, said atomizer having a small reservoir, a supplemental reservoir outside of the bowl, and a siphon for feeding the atomizer reservoir from said supplemental reservoir. 80

In witness whereof, I hereunto subscribe my name this 19th day of February A. D., 1910.

JULIAN G. GOODHUE.
